UNITED STATES PATENT OFFICE.

FREDERICK S. PHELPS, OF SAUSALITO, CALIFORNIA, ASSIGNOR TO THE AMERICAN STEEL AND WIRE COMPANY OF NEW JERSEY, A CORPORATION OF NEW JERSEY.

WIRE ROPE.

1,373,632.

Specification of Letters Patent.

Patented Apr. 5, 1921.

Application filed August 25, 1920. Serial No. 405,956.

To all whom it may concern:

Be it known that I, FREDERICK S. PHELPS, a citizen of the United States, and resident of Sausalito, in the county of Marin and State of California, have invented certain new and useful Improvements in Wire Ropes, of which the following is a specification.

My invention relates to wire ropes having one or more strands, and more particularly relates to the construction of the rope strands, (or when a single strand rope, the strand) of which the rope is made.

One object of the invention is to provide a rope or rope strand of improved construction wherein a series of wires of varying diameter are compactly assembled in a highly novel manner to the end of forming a strand in one operation which combines great strength and flexibility with a maximum cross section of metallic area for any given diameter.

Another object of this invention is the provision of a wire rope strand wherein a series of round wires of selected sizes or diameters are stranded so as to avoid the nicking associated with the cross-lay present in existing constructions.

A further object of the invention is to provide a wire rope strand wherein the wires are helically wound around a central core and are locked in assembled position, so that displacement thereof when in service is overcome and prevented.

A further object of the invention is to provide a wire rope strand wherein all of the wires in the outer layer are of the same diameter, each wire thereby offering the same amount of resistance to abrasion.

A still further object of this invention is the provision of a wire rope or rope strand having the novel arrangements and combinations of round wires shown by the drawing, hereinafter described in detail, and particularly pointed out in the appended claims.

In the accompanying drawing, forming part of this specification, Figure 1 is a plan showing a short length of a wire rope having the strands thereof constructed and arranged in accordance with my invention.

Fig. 2 is a section, on an exaggerated scale, showing a rope strand embodying the

novel features of my invention, the section begin taken on the line II—II of Fig. 1.

55

Referring now to the drawing, each rope strand has a core 2 preferably formed of a single wire of relatively large diameter. However, when desired, the core 2 may be made of hemp or similar material. The core 60 2 is surrounded by a layer of wires 3, which are helically wound, side by side, upon the core 2. The wires forming this inner layer of wires are all of the same diameter and somewhat smaller than the central core 2. 65

The inner layer formed by the wires 3 is surrounded by an intermediate layer of wires which are helically wound and extend in the same direction as the wires 3. This intermediate layer is formed of double 70 the number of wires in the inner layer and has alternate large wires 4 and small wires 5. The wires 4 and 5 are of such relative size as will completely cover the inner layer of wires and at the same time form 75 a true circle.

In assembling the intermediate layer, the large wires 4 are arranged to lie in the interstices between the wires 3 forming the inner layer, being thereby locked firmly in 80 place, and the smaller wires 5 are positioned on the crowns of the wires 3 of the inner layer and between the wires 4 of the intermediate layer.

The intermediate layer formed by the 85 wires 4 and 5 is surrounded by a third or outer layer of wires 6, the number of wires in this outer layer being equal to the number in the second layer, but being of greater diameter than the wires in either the inner 90 or intermediate layer of wires. The wires 6, which also are wound helically, are laid in the interstices between the wires of the intermediate layer and are arranged to cover the intermediate layer and form a true circle, as well as being locked against displacement. 95

In forming a rope having a plurality of strands, the strands after being formed will be laid up into a rope in any desired one of 100 the several known manners, but preferably will be arranged as shown in Fig. 1.

The advantages of my invention will be apparent to those skilled in the art. By arranging the strand wires in layers and by 105 selecting the sizes of the various wires, a

strand or rope is obtained which is strong and flexible and which is of minimum diameter, and has a maximum amount of metal for that diameter. By arranging the wires 5 in the manner shown and described all of the wires in the outer layer are completely locked in position, and the wires of the outer layer being of the same diameter, each wire offers the same amount of resistance to 10 abrasion. This feature is of great importance because it permits of larger wires being used in the outer layer of wires than is possible in the rope strand as heretofore constructed. All of the wires being laid up in 15 one operation in forming the strands, nicking is avoided and the wires have a line bearing on adjacent wires instead of the point bearing usually present in flexible wire ropes of ordinary construction.

20 Modifications in the construction and arrangement of the wires forming my improved rope may be made without departing from the invention as defined in the appended claims.

25 I claim:—

1. A wire rope or strand formed of round wires and comprising a core, an inner layer of wires wound helically around said core, an intermediate layer of wires surrounding 30 said inner layer, the wires in said intermediate layer being double the number in said inner layer and having alternate wires lying in the interstices between the wires of said inner layer, and an outer layer of wires 35 surrounding said intermediate layer and having the wires in said outer layer lying in the interstices between the wires of said intermediate layer.
2. A wire rope or strand formed of round 40 wires and comprising a core, an inner layer of wires wound helically around said core, the diameter of the wires in said inner layer being smaller than the diameter of the core, an intermediate layer of alternating large 45 and small wires surrounding said inner layer, the wires in said intermediate layer being double the number in said inner layer, and the larger wires of said intermediate 50 layer lying in the interstices between the wires of the inner layer, and an outer layer of wires surrounding said intermediate

layer, the wires in said outer layer lying in the interstices between the wires of said intermediate layer.

3. A wire rope or strand formed of round 55 wires and comprising a core, an inner layer of wires wound helically around said core, the diameter of the wires in said inner layer being smaller than the diameter of the core, an intermediate layer of alternating large 60 and small wires surrounding said inner layer, the wires in said intermediate layer being double the number in said inner layer, and the larger wires of said intermediate 65 layer lying in the interstices between the wires of the inner layer, and an outer layer of wires surrounding said intermediate layer, the wires of said outer layer lying in the interstices between the wires of the intermediate layer and being of greater diameter 70 than the wires in said intermediate layer.

4. A wire rope or strand formed of round 75 wires and comprising a core and a plurality of concentric layers of wires surrounding 80 said core, the wires in the inner layer being wound helically around the core, the wires in the intermediate layer being double the number in the inner layer and having alternate wires lying in the interstices between 85 the wires of said inner layer, and the wires in the outer layer equaling the number in the intermediate layer and lying in the interstices between the wires of said intermediate layer.

5. A wire rope or strand formed of round 90 wires and comprising a core and a plurality of concentric layers of wires surrounding said core, the wires in the inner layer being wound helically around the core, the wires in the intermediate layer being double the number in the inner layer and being formed of alternating large and small wires, with the series of larger wires lying in the interstices between the wires of said inner layer, 95 and the wires of the outer layer of larger diameter than the wires in said intermediate layer and lying in the interstices between the wires forming said intermediate layer.

In testimony whereof, I have hereunto 100 signed my name.

FREDERICK S. PHELPS.
